Primary Examiner — Darlington Ly*Assistant Examiner* — D. Ryan Tisdale(74) *Attorney, Agent, or Firm* — Plumsea Law Group, LLC(57) **CLAIM**

The ornamental design for a front grille for automobile, as shown and described.

DESCRIPTION

FIG. 1 is a front and left side perspective view of a front grille for automobile embodying my new design;

FIG. 2 is a rear and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The ghosted or low contrasted areas illustrate portions of the front grille that form no part of the claimed design.
